UNITED STATES PATENT OFFICE.

WILLIAM JAMES HUTCHINSON, OF TORONTO, ONTARIO, CANADA.

APPLIANCE FOR ADJUSTING THE FOLDING TOPS OF VEHICLES.

1,073,900.

Specification of Letters Patent.

Patented Sept. 23, 1913.

Application filed December 16, 1912. Serial No. 737,075.

To all whom it may concern:

Be it known that I, WILLIAM JAMES HUTCHINSON, of the city of Toronto, in the county of York, in the Province of Ontario, 5 Canada, have invented certain new and useful Improvements in Appliances for Adjusting the Folding Tops of Vehicles, of which the following is the specification.

My invention relates to improvements in 10 appliances for adjusting the folding tops of vehicles and the object of the invention is to devise an appliance of this class whereby the top head piece of a closed vehicle and folding top of an open vehicle may be raised 15 or lowered to the closed or open position without the necessity of the occupant of the vehicle having to alight from the vehicle and it consists essentially of a lever secured to the front post of the head piece and to 20 which the links supporting the head piece are connected, a turnable rod journaled in the body of the vehicle, a cord extending up from such rod to one arm of the aforesaid lever and over suitably arranged pulleys, a cord also extending from the same 25 arm of the lever, a tension spring to which the opposite end of the cord is connected, means for rotating the turnable shaft and means for locking the shaft in the position 30 to which it is turned as hereinafter more particularly explained.

Figure 1, is a general perspective view, 35 partially broken away and in section, of the back portion of a vehicle and the head piece thereof. Fig. 2, is a cross section through Fig. 1. Figs. 3 and 4 are details of the tension spring. Fig. 5, is an enlarged detail of the operating lever. Fig. 6, is a similar view to Fig. 5 looking at right angles 40 thereto.

In the drawings like letters of reference indicate corresponding parts in each figure.

A is the body of the vehicle provided with the usual frame A' having the inner lining 45 A² and the outer shell A³ provided with a lining A⁴ in the inner wall A⁵.

B is the head piece provided with front braces B' and cover B² supported by the braces B³ in the usual manner.

50 B⁶ is a bell crank lever comprising arms B⁷ and B⁸ connected by the braces B⁹.

B¹⁰ are lugs extending from the arm B⁷ and to which the braces B³ are pivotally connected.

55 C is the bottom of the vehicle and to which are secured the bearings C' and C².

C³ is an operating shaft journaled in the bearings C' and C².

C⁴ is a double ratchet gear secured to the shaft C³.

60 D is a hood covering the ratchet C⁴ and secured to the floor C.

D' is a spring plunger held within the socket D² forming part of the hood. The plunger D' normally engages with the 65 ratchet wheel C⁴ to hold it in the required position.

D³ is a button for withdrawing the spring plunger when necessary.

E is a lever also swung on the shaft C³. 70

F are spools secured on the shaft C³ in proximity to each end thereof.

F' is a pulley secured in suitable bearings between the lining A² and the lining A⁴.

75 F² is a pulley (see Fig. 2) journaled in suitable bearings secured to the inside of the wall A⁵.

F³ is a cord secured at one end to the arm B⁹ and extending over the pulleys F' and F² to the spools F to which it is secured. 80

G are tension springs secured at one end to brackets G' located between the linings A² and A⁴. The opposite ends of the springs are connected together by a plate G². G³ and G⁴ are pulleys also suitably journaled 85 between the linings A² and A⁴.

G⁵ is a cord extending from the arm B⁹ of the lever over the pulleys G⁴ and G³ to the plate G² to which it is suitably secured.

90 It will, of course, be understood that there are a series of pulleys, operating cords and tension springs connected to similar levers located at each side of the top head piece as indicated by dotted lines in Fig. 1.

I is an operating lever provided with a 95 plunger I' engaging the ratchet C⁴.

When the occupant of the vehicle desires to lower the top head piece all he has to do is to swing the lever E downwardly so as to wind the cords B⁹ around the spools F. 100 This operation draws the arm B⁸ of the lever downwardly in the direction of arrow so as to lower the head piece in to the position shown by dotted lines.

It will be readily seen that by the downward movement of the arm B⁸ that the springs G are drawn in to tension by the cord G⁵ connecting the springs to the arm B⁹.

105 The spring plunger D' serves to prevent the return movement of the ratchet C⁴ when the head piece is thrown in to the depressed

position holding the head piece in such position until the plunger is withdrawn by means of the button D². When the occupant of the vehicle desires to raise the hood the withdrawal of the plunger D' and spring G act to pull the arm G⁸ upwardly in the reverse direction of arrow thereby raising the head piece in to the position shown in the drawings.

10 If it be desired to have the driver of the vehicle to operate the head-piece instead of the occupant of the vehicle, a supplemental pulley H^x may be employed as disclosed by Fig. 1, around which may extend a cord H¹ secured to a spool (not shown) in the shaft C³, said cord being operable from the pulley H^x and a lever H², similar to the lever H.

Although I have shown my device as applied to a closed vehicle it will of course be understood that the device may be equally well adapted to what are technically known as open vehicles such as touring cars and the like.

What I claim as my invention is:

25 1. In an adjusting appliance for folding tops for vehicles, the combination with the body of the vehicle and the folding top frame hinged in the usual manner to the body, of a lever extending outwardly in a substantially horizontal direction from the

hinged point at each side of the frame, an operating shaft journaled in the body of the vehicle, a tension spring located in the body, cords extending from the aforesaid lever over suitable pulleys to the tension spring, 35 locking means for the operating shaft, and a cord extending from the shaft over suitable pulleys to the aforesaid lever, as and for the purpose specified.

2. In an adjusting appliance for top head 40 pieces for closed vehicles, the combination with the body and the frame of the head piece hinged in the usual manner to the body, a lever extending outwardly from the hinged point, an operating shaft, a ratchet 45 wheel on the shaft, a spring locking plunger co-acting therewith, an operating lever mounted on the shaft and co-acting with the ratchet, pulleys suitably journaled in the body, tension springs secured within the 50 body, a cord extending from the operating shaft over the pulleys to the lever arm, and a cord extending from the tension springs over pulleys to the lever arm, as and for the purpose specified.

WILLIAM JAMES HUTCHINSON.
